UNITED STATES PATENT OFFICE

92,441

DESIGN FOR A WARM AIR FURNACE HEATING ELEMENT

Walter W. Williams, Bloomington, Ill.

Application October 18, 1933, Serial No. 49,510

Term of patent 7 years

To all whom it may concern:

Be it known that I, WALTER W. WILLIAMS, a citizen of the United States, residing at Bloomington, in the county of McLean and State of Illinois, have invented a new, original, and ornamental Design for Warm Air Furnace Heating Elements, of which the following is a specification, reference being had to the accompanying drawing, forming part thereof,

In the drawing:

Figure 1 is a top plan view of my new design for a warm air furnace heating element.

Figure 2 is a view in side elevation of Figure 1.

Figure 3 is a view in end elevation of Figure 1.

I claim:

The ornamental design for a warm air furnace heating element, as shown.

W. W. WILLIAMS.
